UNITED STATES PATENT OFFICE.

HARRY J. WARTHEN, OF WASHINGTON, DISTRICT OF COLUMBIA.

AUTOMATIC AIR-BRAKE CONTROL FOR RAILWAYS.

1,090,806.

Specification of Letters Patent. Patented Mar. 17, 1914.

Application filed June 16, 1910, Serial No. 567,301. Renewed February 5, 1914. Serial No. 816,843.

To all whom it may concern:

Be it known that I, HARRY J. WARTHEN, a citizen of the United States, residing in the city of Washington, District of Columbia, have invented an Automatic Air-Brake Control for Railways, of which the following is a full and complete specification.

This invention is an improvement in signal devices for railways, and relates more especially to a control mechanism for automatically applying the air-brakes to a train when the electric signal circuit is broken from any cause.

The primary object of the present invention is to provide certain devices which are applied to the air-brake system and normally maintained by a closed electric circuit so as not to interfere with the usual operation of the air-brake mechanism, and so constructed and arranged with respect to the fluid-pressure supply to the train-line that when the electric circuit is broken, from any cause, the devices will operate by gravity to exhaust the train-line and thus apply the brakes to the train.

A further object of my present invention is to provide the automatic air-brake control devices with means whereby said devices may be restored to the normal position by the operation of the engineer's starting-lever.

With these principal objects in view my invention consists in providing the fluid-pressure supply of an air-brake system with a valve through which the fluid-pressure passes to the train-line, means for maintaining the valve in open position by a closed electric circuit and for closing the valve by gravity when the electric circuit is broken; all as hereinafter fully described and specifically set forth in the appended claims.

In the accompanying drawings, which form a part of this specification: Figure 1 is a view of an air-brake control mechanism constructed in accordance with my invention, the parts being shown in their normal position, with the electric circuit closed. Fig. 2 is a similar view, illustrating the position of the parts when the circuit is broken.

Like numerals of reference indicate like parts in both figures of the drawings.

In carrying out my invention I provide the supply-pipe 4 from the fluid-pressure reservoir 5 to the train-line connection 6 of the air-brake system of a railway train

with a piston-valve comprising a cylindrical casing 7 and vertically movable piston 8, the latter having a horizontal passage 9 which connects the supply-pipe 4 with the train-line connection 6 when said piston is raised, as shown in Fig. 1. This piston is also provided with a cavity 8^a in its upper side adapted to connect the train-line connection 6 with an exhaust-port 7^a in the cylinder when the piston is lowered to cut off the supply to the train-line, as shown in Fig. 2 of the drawings, and for the purpose of operating the piston the cylinder is connected at its lower end to the fluid-pressure reservoir 5 by feed pipes 10 and 11, with an interposed control-valve comprising a casting 12 and turning-plug 13, the latter having a passage 14 for connecting the feed pipes 10 and 11, and a cavity 15 for connecting the pipe 10 with an exhaust port 16. The turning-plug of the control-valve has an operating-arm 17 connected to the staff 18 of a solenoid 19, the connections being such that the control-valve is open to connect the piston-valve with the fluid-pressure reservoir, and hold the piston 8 raised, when the solenoid is energized, and is closed to exhaust the air-pressure below the piston-valve so that the latter will drop and cut off the supply to the train-line connection 6 when the solenoid is deenergized, the latter operation being effected by the gravity of the solenoid-staff augmented by a weight 20 on the upper end of said staff.

The electric connections for the solenoid are from one side of a battery 21 by wire 22 to one side of the solenoid, from the other side of said solenoid by wire 23 to a make and break device—in the present instance a switch 24—and by wire 25 from the switch to the other side of the battery. A lamp, 26, preferably showing a white light, is connected to the wires 22 and 23, at opposite sides of the solenoid, so that said lamp will be lighted when the solenoid is energized; and in order to show a red light, when the solenoid is deenergized, I provide a lamp 30 for this purpose, and in the circuit of this lamp are spaced apart contacts 27, 27, with which a plate 31 on the staff of the solenoid co-operates to close the circuit; one of the contact-points 27 being connected by wire 28 to wire 22 extending to one side of battery 21, and the other contact-point 27 by wire 29 to the wire 25 extending to the other side of said battery, the plate 31 being at

tached to the staff of the solenoid so as to rest on the contact-points when the solenoid is deenergized, and to break the red-lamp circuit when the solenoid is energized, as will be obvious.

For the purpose of raising the staff of the solenoid and thereby operating the control-valve independently of the electric circuit and restore a normal condition to the air-brake system, I provide a piston 32 operating in a cylinder 33 and connected to the lower end of the staff of the solenoid, the lower end of the cylinder being connected by a pipe 34 to the upper end of a cylinder 35, in which latter operates a piston 36. By this arrangement, when piston 36 is raised in cylinder 35 it will compress the air in the upper part of said cylinder and force it through pipe 34 to cylinder 33, thus lifting piston 32 and staff 18 connected thereto. The piston 36 is operated by a pivoted lever 37 engaging the curved lower end of said piston, and in the present instance this operating lever is connected by rod 38 to the engineer's operating lever 39, the arrangement of levers being such that lever 37 will be operated to raise piston 36 only when the engineer's operating lever is moved to reverse the engine; whereby the train may be backed but cannot proceed forward until the electric circuit is closed to hold the staff of the solenoid up.

For the purpose of illustrating the operation of the electric circuit in connection with the control devices, I have herein illustrated the circuit as controlled by an ordinary switch; but in practice this circuit is controlled by certain track-circuits forming the subject-matter of a companion application for patent filed on even date herewith.

The operation of the control devices will be readily understood by reference to the accompanying drawings; for it will be seen that when the parts are in normal position and maintained by a closed circuit, as shown in Fig. 1 of the drawings, the fluid-pressure from the main reservoir 5 of the air-brake system may pass by pipe 4 through piston-valve 8 to the pipe 6 which connects with the usual train line, permitting the air-brake mechanism to be operated by the engineer in the usual manner, the piston 8 in this instance being held raised by pressure from reservoir 5 through control-valve 13 to the underside of said piston, and the control-valve held open by the solenoid. In this normal position of the parts lamp 26 showing a white light will be lighted, and the lamp 30 showing a red light extinguished by reason of the plate 31 being raised. Now should the electric circuit be broken from any cause the solenoid becomes deenergized and the weighted staff 18 falls by gravity thus closing control-valve 13 so that the pressure to cylinder 7 is cut off and said cyl-

inder exhausted, allowing piston 8 to drop and cut off the fluid-pressure supply to the train-line; thereby automatically applying the air-brakes to the train. As will be seen, therefore, the control devices operate by gravity, and are maintained in normal position by a closed electric circuit.

When a train is stopped by the breaking of the electric circuit the engineer cannot proceed with his train until the circuit is closed again, but may temporarily restore the devices to normal condition so as to back his train by moving the operating lever to reverse position.

Having thus described my invention, what I claim as new and desire to secure by Letters-Patent, is:—

1. An air-brake control device for railway trains, in combination with a fluid-pressure supply and train-pipe, of a piston-valve through which the fluid-pressure passes to the train-pipe, a control-valve for admitting fluid-pressure to the piston-valve, a solenoid having a weighted staff for closing the control-valve, and an electric circuit for the solenoid to open said control valve.

2. An air-brake control device for railway trains, in combination with a fluid-pressure supply and train-pipe, of a piston-valve through which the fluid-pressure passes to the train-pipe, a control-valve for admitting fluid-pressure to the piston-valve, a solenoid or electro-magnet for operating the control-valve, an electric circuit energizing the solenoid or electro-magnet, a make and break device for the electric-circuit, and means operated by the engineer's starting lever for restoring the solenoid or electro-magnet to normal position.

3. An air-brake control device for railway trains, in combination with a fluid-pressure supply and train-pipe, of a valve through which the fluid-pressure passes to the train-pipe, a solenoid or electro-magnet and means operated thereby for controlling the valve, an electric-circuit energizing the solenoid or electro-magnet, a make and break device for the electric circuit, and means operated by the engineer's starting lever for restoring the solenoid or electro-magnet to normal position independently of the circuit.

4. An air-brake control device for railway trains, in combination with a fluid-pressure supply and train-pipe, of a piston-valve having a gravity-operated piston through which fluid-pressure passes to the train-pipe when said piston is raised, a control-valve for admitting pressure to the piston-valve to hold the piston normally raised, a solenoid having a weighted staff connected to the control-valve for holding the latter normally open and for closing it by gravity when the solenoid is deenergized, an electric-circuit for the solenoid, a piston connected to the staff of the solenoid, a piston connected

cylinder, a second cylinder connected to the lower part of the first mentioned cylinder, a piston in the last mentioned cylinder, and means for operating said piston from the 5 engineer's operating lever, substantially as shown and described.

In testimony whereof I have signed my

name to this specification in the presence of two subscribing witnesses.

HARRY J. WARTHEN.
